GRATE BAR

Filed June 22, 1927

UNITED STATES PATENT OFFICE

GEORGE H. THACHER, JR., OF MELROSE, MASSACHUSETTS

GRATE BAR

Application filed June 22, 1927. Serial No. 200,725.

This invention relates to grate bars and more particularly to the novel construction of the grate blocks mounted upon the bars.

The stoker bars or grate bars of the present invention are designed more particularly for use in a mechanical stoker such as shown and described in my co-pending application Ser. No. 165,088, filed February 1, 1927, and are particularly well adapted to withstand the high temperatures to which they may be subjected.

Grate or stoker bars as usually constructed heretofore have been of the rocking type which are open to the objection that when the bars are rocked or tilted to shake the fuel bed, the projections or fingers upon the grate bars that are forced upwardly into the fuel bed are subjected to an intense heat that tends to destroy them.

The grate bars of the present invention are supported for sliding movement towards and from the fuel bed in a direction at substantial right angles to the plane of the fuel bed, and as a result the edges of the grate bars are not tilted upwardly into the fuel bed as in the rocking type of grate. This feature alone materially reduces the destructive action of the heat of the fuel bed upon the grate bars.

The upward sliding movement imparted to the present grate bars has a further advantage in that it permits a construction whereby the grate bars may be cooled much more effectively than heretofore by the air passing upwardly through the grate.

An important feature of the invention resides in a bar having a series of grate blocks mounted thereupon and provided with downwardly extending side walls disposed in spaced relation to the bar so that the cooling currents of air may pass upwardly at each side of the bar between the sides of the bar and the spaced side walls of the blocks mounted thereupon.

A further feature of the invention resides in the construction of the grate blocks whereby the surfaces thereof that come in contact with the fuel bed are free from exposed projections that will be burnt off by the heat of the fuel.

Another important feature of the present invention resides in the construction of the hollow grate blocks whereby all walls and partitions of a block have substantially the same thickness and the entire block construction is such that all of the walls and partitions will heat up and cool off at about the same rate, to thereby relieve the block structure from injurious internal stresses.

Other features of the invention and novel combination of parts in addition to the above will be hereinafter described in connection with the accompanying drawings which illustrate one good practical form of the invention.

In the drawings:—

Fig. 1 is a perspective view of a portion of the grate showing the composite grate bars in their operative position;

Fig. 2 is a transverse sectional view taken on the line 2—2 of Fig. 4;

Fig. 3 is a transverse sectional view through a supporting bar, the blocks being removed;

Fig. 4 is an enlarged side view of one of the grate bars of Fig. 1; and

Fig. 5 is a longitudinal sectional view through a grate block.

The grate or stoker bars forming the subject matter of the present invention are preferably supported side by side transversely of the furnace, as shown in Fig. 1, and are mounted for sliding movement toward and from the fuel bed at a slight inclination to a vertical plane as clearly set forth in my co-pending application above mentioned. Certain features in the construction of the composite stoker bars of the present invention may however be employed in other grate constructions than that shown and described in said application.

Each grate or stoker bar is shown as consisting of a bar 10 upon which are mounted a series of grate blocks 11. The blocks are preferably six-sided, that is, each block has a box-like construction and is formed with a flat top and approximately parallel side and end walls, and the opposite side walls have smooth flat surfaces that are free from projections and depressions. The blocks are shown in the drawings as resembling a cube

or hexahedron in shape; though if desired their length may be much greater than their width. These blocks preferably have relatively deep side walls 12 and end walls 13 as shown, to increase their radiating surface and also to increase the height of the upper or fuel supporting face of the blocks from their supporting bars 10.

The blocks 11 are made hollow as shown so that cooling currents of air may pass upwardly through them and the blocks are preferably provided with the transversely extending webs 14 which help to support the fuel bed and serve also to increase the radiating surface of the blocks, and between the webs 14 are formed the air passages 15. The end walls 13 and the central web 14 may extend downwardly a sufficient distance to rest upon the supporting bar 10 as will be apparent from Fig. 5 while the webs 14 at each side of the central wall preferably extend downwardly a less distance to facilitate the passage of air into the different passages 15.

In the operation of furnaces and more particularly in the operation of heavy duty commercial furnaces where the grates are subjected to excessively high temperatures, it is of the utmost importance that the grate blocks be so constructed that they may expand and contract freely with changes in temperatures without subjecting any portion of the block to pronounced internal stresses that are likely to crack the block. It is also extremely important that the grate blocks be so constructed that they afford a maximum amount of radiating surface which is exposed to the cooling currents of air passing upwardly through the grate.

The grate blocks of the present invention fulfill these requirements remarkably well, and as a result they are peculiarly well adapted for use in heavy duty commercial furnaces where they are subjected to extremely high temperatures. It should be noted that all walls and partitions or webs of the present blocks are of practically the same thickness, and that the air passage between any two walls of the assembled blocks has approximately the same width as the air passage between any other two walls, with the result that all walls and partitions of a block will heat up and cool off at about the same rate, thus relieving the block structure from injurious internal stresses. Furthermore, since the walls and partitions are disposed in approximately parallel relation and extend downwardly a substantial distance from the upper face of the block, each wall and partition has a large radiating surface which is practically equal to the radiating surface of any other wall or partition of the block.

These features are believed to be broadly new, and it is found in practice that furnaces

which are provided with grates constructed in accordance with the present invention may be operated successfully month after month at high temperatures which heretofore were considered impractical, due to their destructive action upon the grates previously employed. The excellent results secured by the present grates is due to the above described construction, whereby, is secured to a high degree, (1) Equal expansion throughout the 75 grate block; (2) Equal radiation for all portions of the block and (3) A large percentage of radiating surface as compared with the metal surface exposed to the fire.

The blocks 11 are secured to the bar 10 in the construction shown by extending the side portions of the central web 14 downwardly to form the fingers 16 that straddle the bar 10, and these fingers are received in grooves or slots 17 formed between the spaced projections 18 upon the bar 10. As a result of this construction the blocks 11 are secured to the bar 10 in spaced relation to each other as shown, while at the same time they are free to expand lengthwise of the bar in opposite directions from their securing means. The blocks 11 may be further fastened to the bar 10 by providing pins 19 that extend transversely of the fingers 16 beneath the projections 18 as will be apparent from Fig. 2; 95 the construction being such that the blocks are prevented by the pins 19 from being accidentally disengaged from the bar 10. Since the present grate bars are not subjected to a rocking movement, as is customary in 100 most stoker mechanisms, the grate blocks are easier to retain in place than the rocking grate blocks or caps, and as a result a pair of fingers 16 disposed in the transverse central plane of the block 11 will serve to retain 105 the block in place upon the bar 10, while this construction permits the opposite end portions of the block to expand freely lengthwise of the bar from the central securing means. The major portion of the bar 10, it 110 will be noted, is relatively narrow in cross-section. This construction is desirable to permit a free passage of air upwardly through the hollow blocks 11 at each side of the supporting bar.

As above indicated the bars 10 are preferably mounted for sliding movement towards and from the fuel bed and to this end the bars 10 are provided at their opposite ends with the downwardly extending projections 20 120 adapted to guide the bars in their sliding movement. The transversely extending bars 10 are supported at their opposite ends upon the longitudinally extending beams 21 which are more fully shown and described in my 125 application above mentioned, and to the opposite faces of the supporting beams 21 are secured the spaced blocks or angle irons 22 between which are provided slideways adapted to receive the projections 20. The lower 130

ends of the projections 20 normally rest upon the lugs 23 formed upon the supporting beams, and the construction is such that the fuel engaging grate blocks 11 are held by the construction just described at a substantial distance above the beams 21, thus relieving these beams from the intense heat of the fuel bed. The composite grate or stoker bars may be raised and lowered to manipulate the fuel bed by links 24 the upper ends of which are connected to lugs 25 provided upon the bars 10, and the lower ends of these links may be connected to rocking bars 26, but since the mechanism for raising and lowering the grate bars forms no part of the present invention and is fully shown and described in said application, a further disclosure of the same herein is believed to be unnecessary.

20 The opposite ends of the grate blocks 11 are preferably provided with the grooves 27 arranged to cooperate with adjacent blocks to form the air passages 28 between a pair of blocks, and the depth of the side walls 12 of the blocks is preferably such that the side walls of adjacent blocks will overlap each other even when a grate bar is raised to its maximum position of elevation as shown at the right-hand side of Fig. 1 of the drawings. 30 In other words, each side wall 12 of a block extends downwardly below the upper edge of the supporting bar 10 and forms an apron that lies in spaced relation to the bar throughout the length of the block, thus increasing the radiating surface.

This construction prevents a large opening from occurring between adjacent stoker bars when one is raised while the other is in its normal or lowered position, and also prevents 40 clinkers from lodging between adjacent bars to interfere with their sliding movement. The hollow grate blocks 11 herein described are free from projecting lugs or fingers which are forced upwardly into the fuel bed to be 45 burnt off by the high temperature of the fuel, and the entire structure is such that the composite grate or stoker bars formed in accordance with the present invention will withstand the high temperature of a furnace 50 much better than the stoker bars employed heretofore.

What is claimed is:—

1. In a furnace grate, in combination, a 55 grate bar, an approximately cubical grate block mounted on said bar in straddling relation therewith and provided with a flat upper face and deep side and end walls that extend downwardly from the upper face of the block a distance nearly equal to the length 60 of the block to provide heat radiating walls, the lower ends of said side walls being disposed in spaced relation to the grate bar to form well defined air passages leading upwardly into the block at each side of said bar, said side walls being disposed in substantial-

ly parallel relation to each other and provided with flat smooth outer surfaces, and partitions extending transversely of the block in spaced relation to each other to form long vertical air passages, extending upwardly 70 through the block.

2. In a furnace grate, in combination, a 75 grate bar provided with substantially parallel side faces, a series of grate blocks mounted on said bar in straddling relation therewith and each comprising a substantially cubical hollow block provided with a flat upper face and deep end walls and deep flat side walls, said side walls being smooth and flat and practically parallel and constructed 80 to extend downwardly a pronounced distance from the upper face of the block into the cooler zone beneath the fuel bed and disposed in spaced relation to said side faces of the 85 grate bar to form well defined air passages leading upwardly into the block at each side of said bar, and partitions extending between the side walls of the block to provide vertical air passages extending upwardly through the block from a position well below the fuel 90 bed.

3. In a furnace grate, in combination, a 95 grate bar provided with approximately parallel side faces, a hollow substantially cubical grate block mounted on the bar in straddling relation therewith and provided with block positioning surfaces adapted to engage the side faces of the bar, said block being provided with end walls and deep substantially 100 parallel side walls, the side walls being smooth and flat and constructed to extend downwardly below the upper face of the grate bar in spaced relation to its side faces to form well defined air passages leading 105 upwardly into the block at each side of said bar, and partitions formed between the walls of the block to provide air passages extending upwardly through the block so that air enters the interior of the block from points well below the upper edge of the grate bar. 110

4. In a furnace grate, in combination, a 115 grate bar, a hollow approximately cubical grate block mounted on the bar and provided with notched end walls extending downwardly into straddling relation with the centrally disposed bar, said block being provided with smooth and flat side walls that are substantially parallel and constructed to extend downwardly a substantial distance below the upper face of the grate bar in spaced 120 relation to the sides of said bar to form well defined air passages leading upwardly into the block at each side of said bar, and partitions formed between the walls of the block 125 to provide air passages leading upwardly through the block from a point below the upper edge of the grate bar.

In testimony whereof, I have signed my name to this specification.

GEORGE H. THACHER, JR. K
